US0D1017535S

(12) **United States Design Patent** (10) **Patent No.:** **US D1,017,535 S**
(45) **Date of Patent:** **** Mar. 12, 2024**

(54) **CHARGING STANCHION**

(71) Applicant: **Parabit Systems, Inc.**, Roosevelt, NY (US)

(72) Inventors: **Robert J. Leiponis**, Glen Cove, NY (US); **Wilson M. Lee**, Valley Stream, NY (US); **Donald W. Strong**, Rochester, NY (US)

(73) Assignee: **Parabit Systems, Inc.**, Roosevelt, NY (US)

(**) Term: **15 Years**

(21) Appl. No.: **29/830,097**

(22) Filed: **Mar. 10, 2022**

(51) LOC (14) Cl. **13-02**

(52) U.S. Cl.

USPC **D13/107**

(58) **Field of Classification Search**

USPC ... D13/107, 108, 118, 119, 120, 121, 137.1, D13/139, 184, 199; D14/900

CPC H02J 7/0045; H02J 7/0044; H02J 7/02; H02J 7/00; B60L 53/10; B60L 53/16

(57) **CLAIM**

The ornamental design for a charging stanchion, as shown and described.

DESCRIPTION

FIG. 1 is a front, top, right perspective view of a charging stanchion showing our new design;

FIG. 2 is rear, top, left perspective view thereof;

FIG. 3 is a top plan view thereof;

FIG. 4 is a bottom plan view thereof;

FIG. 5 is a front elevational view thereof;

FIG. 6 is a right side elevational view thereof;

FIG. 7 is a rear elevational view thereof; and,

FIG. 8 is a left side elevational view thereof.

The broken lines in the drawings depict portions of the charging stanchion that form no part of the claimed design.

1 Claim, 5 Drawing Sheets
